UNITED STATES PATENT OFFICE.

ALFRED J. FLAUDER, OF BRIDGEPORT, CONNECTICUT, ASSIGNOR TO THE WEIDLICH BROTHERS MANUFACTURING CO., OF BRIDGEPORT, CONNECTICUT, A CORPORATION OF CONNECTICUT.

DESIGN FOR A CLOCK-CASE.

44,557.

Specification for Design.

Patented Aug. 26, 1913.

Application filed June 28, 1913. Serial No. 776,436. Term of patent 3½ years.

To all whom it may concern:

Be it known that I, ALFRED J. FLAUDER, a subject of the King of Austria, and resident of Bridgeport, in the county of Fairfield and State of Connecticut, have invented a new, original, ornamental, and colonial Design for a Clock-Case, of which the following is a specification, reference being had to the accompanying drawings, forming part thereof.

In the drawings: Figure 1, shows a front elevation of my new design of clock. Fig. 2 shows a right hand side view of the same.

Fig. 3, is a rear elevation of the clock case. Fig. 4 is a left hand side view and Fig. 5, is a top plan view of the same.

I claim:

The ornamental design for a clock case as shown.

Signed at Bridgeport in the county of Fairfield and State of Connecticut, June, A. D. 1913.

ALFRED J. FLAUDER.
